UNITED STATES PATENT OFFICE.

SAMUEL IDE, OF MEDINA, NEW YORK.

LATHE-CHUCK.

SPECIFICATION forming part of Letters Patent No. 400,459, dated April 2, 1889.

Application filed January 31, 1889. Serial No. 298,196. (No model.)

To all whom it may concern:

Be it known that I, SAMUEL IDE, a citizen of the United States, residing at Medina, in the county of Orleans and State of New York, 5 have invented a new and useful Improvement in Centering-Jaws for Lathe-Chucks, of which the following is a specification.

My invention relates to an improvement in centering-jaws for lathe-chucks; and it consists in a jaw having a series of steps or shoulders, set-screws working in threaded openings in the jaw and communicating with the vertical faces of the shoulders, and adjustable rods working in openings in said 15 jaw on a level with the horizontal faces of its steps or shoulders, and set-screws to retain said adjustable rods; and my invention further consists in the peculiar construction and combination of devices, that will be more fully 20 set forth hereinafter, and particularly pointed out in the claims.

In the drawings, Figure 1 is a perspective view of a lathe-chuck provided with jaws embodying my improvement. Fig. 2 is a detailed longitudinal sectional view of one of my improved jaws. Fig. 3 is a sectional view of the same, taken on the line $x x$ of Fig. 2. Fig. 4 is a detail view of one of the clamping-screws, and Fig. 5 is a similar view of one of 30 the adjustable rods.

The chuck A is provided with the usual radial ways, B, in which are fitted the adjustable centering-jaws C, the same being operated by screws in the usual well-known manner. Each of my improved jaws C is constructed with a series of steps or shoulders, D, the inner vertical faces, E, of which are concentric with the center of the chuck. Threaded openings F are made longitudinally 35 through the jaw, and communicate with the said concentric faces of its shoulders or steps, and in the said openings are screws G, which are adapted to clamp the work or object, have their outer ends squared, and thereby adapted 40 to be turned by a wrench, and having their inner ends pointed in conical form, as at H, and then truncated and provided with conical countersunk openings I, whereby annular biting-edges K are formed between the conical sides H and the conical recesses I, the said 45 edges being adapted to impinge upon and

take into the work so securely as to effectually retain the work in position between the jaws and obviate the possibility of its being dislodged therefrom by the vibration caused 55 by the cutting-tool. Also, extending longitudinally through the jaw are openings L, the inner ends of which communicate with the concentric faces of the jaw at a point on a level with the horizontal planes thereof, as 60 shown. In each of the said openings is arranged a longitudinally-movable adjustable rod, M, said rods having longitudinal recesses N on one side. Transverse threaded openings O are made in the jaw and communicate 65 with the openings L, and in said openings are set-screws P, the inner ends of which enter the recesses N of the rods M, and hence limit the longitudinal movement of said rods and serve to clamp and retain the same at any desired 70 adjustment.

Ordinarily the work is engaged only by the concentric faces of the jaws and by the screws G. When the work has to be bored entirely through, the rods M are moved outward and 75 interposed between the work and the bottoms or horizontal sides of the shoulders, thereby holding the work out of contact therewith, and consequently preventing the point of the 80 boring-tool from defacing the jaws after passing through the work. The screws G are employed to clamp the work firmly between the jaws, as before.

Having thus described my invention, I 85 claim—

1. A lathe-chuck jaw having clamping-screws, one or more, said screws having the annular biting-edges K at their inner ends, substantially as described.
2. A lathe-chuck jaw having the clamping-screws G, with their inner ends having the conical sides H, and provided with the conical central recesses, I, whereby the cones H are truncated, and whereby annular biting-edges K are formed between the conical sides H and the sides of the openings I, substantially as described.
3. A lathe-chuck jaw having the steps or shoulders, the clamping-screws G, and the adjustable rods working in openings in said jaw, for the purpose set forth, substantially as described.

4. A lathe-chuck jaw having the adjustable rods M, one or more, provided with the recesses M, and the set-screws working in threaded openings in the jaw and engaging said recesses, substantially as described.

5. A centering-jaw having a series of steps or shoulders, the clamping-screws G, working through the jaw and communicating with the vertical faces of the steps or shoulders, adjustable rods M, working through the jaw on

a level with the horizontal faces of the steps or shoulders, and set-screws to retain the adjustable rods.

In testimony that I claim the foregoing as my own I have hereto affixed my signature in the presence of two witnesses.

SAMUEL IDE.

Witnesses:

W.M. H. WILMOTH,

FRANK CARPENTER.
